Primary Examiner—Alan P. Douglas*Assistant Examiner*—Jeffrey Asch*Attorney, Agent, or Firm*—James L. Jackson**[57] CLAIM**

The ornamental design for a telephone support device for head mounted use, as shown and described.

DESCRIPTION

FIG. 1 is a front elevational view of a telephone support device for head mounted use showing our new design, the opposite side thereof being a mirror image;

FIG. 2 is a plan view thereof;

FIG. 3 is a side elevational view thereof;

FIG. 4 is an opposite side elevational view thereof; and,

FIG. 5 is a bottom view thereof.

FIG. 2

FIG. 3

FIG. 4

FIG. 1

FIG. 5
